UNITED STATES PATENT OFFICE.

ARTHUR SCHOSHUSSEN, OF WEST SOMERVILLE, MASSACHUSETTS.

BOOT OR SHOE FORM.

Application filed March 31, 1921. Serial No. 457,178.

The present invention relates to forms for boots and shoes, and aims to provide an improved type of adjustable construction, conveniently adapted for neat fitting engagement inside the boot or shoe.

Accordingly, one of the objects in view is to devise an improved shoe form arrangement and construction comprising toe and heel portions, with the toe portion of the form composed of toe sections so connected as to permit separate and independent movement of said sections laterally and angularly with reference to each other for fitting inside the toe portion of the shoe.

It is further sought to provide an improved form of construction of this type in which a connection is made between the heel and toe portions of the form whereby a positive length adjustment of the form is afforded.

A further feature of the construction is an improved type of flexible spring connection between the toe sections of the form, characterized by a novel mode of securing said connecting element to the toe sections.

It is further sought to devise a novel and improved shoe form of this general type in which the toe sections of the form are combined with an instep portion also of sectional form and each toe section being combined with a part of the instep portion.

With the foregoing general objects in view, the invention will now be described by reference to the accompanying drawing illustrating a practical form of embodiment of the improvements, after which the particular features of novelty therein will be pointed out and defined in the appended claims.

In the drawing—

Figure 1 is a side elevation showing a boot or shoe form embodying the present features of improvement, the broken lines representing the heel portion of the form elevated with reference to the toe portion;

Figure 2 is an inverted plan view of the form, with a portion of one of the toe sections broken away to show the manner in which the spring element hereinafter referred to is secured to the toe sections, the broken lines in said view also representing altered positions of the toe sections when shifted to secure an angular adjustment of said sections as required by a different shape of shoe.

Figures 3, 4 and 5 are detail sections taken

on the lines III—III, IV—IV, and V—V, respectively, of Figure 1;

Figure 6 is a side elevation illustrating the toe portion of the form as adapted for pumps or slippers; and

Figure 7 is a longitudinal sectional view showing, on an enlarged scale, a modified form of connection between the toe and heel portions, characterized by a yielding self-adjusting function as regards the length of the form.

Referring now to the drawing in detail, this illustrates the improved form of construction as comprising a heel portion 8 adapted to fit inside the heel or counter portion of the shoe, and a sectional toe portion, made in two half sections 9, and which, in the type of form shown in Figures 1 and 2, is combined with an instep portion 10, each of said toe sections 9 being formed integral with one half of the instep portion 10, and the latter projecting upwardly and rearwardly relatively to said toe portion, as shown in Figure 1. The toe sections 9 are provided with an improved arrangement and construction of connecting means adapted to permit separate and independent movement of said sections 9 both laterally and angularly with reference to each other for fitting within the toe portion of the shoe, an altered position of said sections 9, due to such an adjustment, being represented in the broken lines in Figure 2. This connecting means, in the first place, comprises a flexible coil spring 11 having the opposite ends thereof embedded within recesses 12 formed in the opposed faces of the toe sections 9, and each recess 12 being fitted with a short sleeve element 13 extending somewhat short of the bottom of the corresponding recess 12, thereby permitting the opposite ends of the spring member 11 to be threaded or screwed into the sleeves 13 to the bottoms of the recesses 12 where the ends of the spring may then slightly expand into retaining engagement with the inner ends of the sleeves 13, as clearly illustrated in Figure 4. This unique construction provides a secure retaining means for the ends of the spring element 11, and at the same time permits all of the relative movements required of the forward ends of the toe sections 9 as afforded by the flexible and yielding character of this spring connection 11.

At the rear of the spring element 11 the opposed faces of the toe sections 9 are

formed with mating recesses 14 for accommodating the opposite end portions of a curved or approximately horseshoe-shaped spring member 15, the ends of which are 5 pivotally connected by means of screws 16 to the respective toe sections 9, suitable bearing washers 17 being interposed between the spring terminals and the toe sections at the pivot screws 16, as clearly shown in Figures 10 2 and 5. By this means the requisite expanding function is exerted between the rear end portions of the toe sections 9, and all relative movement necessary is permitted the toe sections for accommodating themselves 15 both laterally and angularly within the shoe for properly fitting the interior of the toe portion thereof. For suitably limiting the said lateral or expanding movement of the toe sections at the rear ends thereof, a link 20 18 is mounted within grooves 19 formed in the instep portions 10 of the form and within the upper portions of said recesses 14, as shown in Figures 2 and 3, and secured to said instep portions 10 by means of screws 25 20. One of the screws 20 slidingly engages a slot 21 in the link 18, whereby a limited degree of relative lateral movement is permitted the toe sections as determined by the length of said slot 21.

30 The mid-portion of the spring member 15 is secured by clamping nuts 22 to the forward end of a turnbuckle connection whereby the toe and the heel portions of the form are adjustably secured 35 together, as illustrated in Figures 1 and 2. This turnbuckle connection comprises a pair of rod sections 23, adjustably connected by means of a turnbuckle nut member 24, the forward rod member 23 being secured to 40 the spring member 15 as already stated, while the rear rod member 23 is preferably threaded into the heel portion 8 of the form, as shown in Figure 1. The middle portion of the turnbuckle member 24 is provided 45 with suitable openings 25 for the application of a pointed instrument for the purpose of rotating the element 24 in either direction as required for the form's adjustment.

The construction which has been de- 50 scribed above, including the instep portion 10, is that type of construction adapted for ordinary high or low top shoes or oxfords, while for pumps or slippers the type of construction illustrated in Figure 6 is pref- 55 erable, wherein the instep portion 10 is omitted, the rest of the form remaining substantially unchanged.

In Figure 7 I illustrate a modified form 60 of connection between the toe and heel portions of the form, the same constituting a certain improvement over the form of connection covered by my co-pending applica- 65 tion Ser. #317,388, filed August 13, 1919, patented July 26, 1921, 1,385,719. As illus- 70 trated herein, this connection comprises a

rod 27 connected to the midportion of the spring member 15 in the same way as the turnbuckle rod 23, and the other end of the rod 27 being slidingly or telescopingly mounted within a sleeve 28 adapted to be 70 connected with the heel portion 8 of the form in the place of the rear turnbuckle rod 23. The forward end of the sleeve 28 is shrunk to provide a retaining lip or shoulder 29 adapted for retaining engagement with the head portion 30 on the rear end of the rod 27. A somewhat larger sleeve or tube 31 is provided for telescoping over the tube or sleeve 28, as well as over a coil spring 32 of substantially the 80 same diameter as the sleeve 28 and interposed between the forward end of the latter and a retaining lip or inturned flange 33 formed upon the forward end of said tube or sleeve 31, whereby the said spring 32 is 85 maintained constantly concealed within the outer tube or sleeve 31. By this construction, the toe and heel portions of the form are automatically separated into self-adjusting relation conforming to the length of the 90 shoe into which the form is fitted, in the same manner as characterizes the device shown in said co-pending application, the present construction having all of the advantages of my earlier type of form, with 95 the added advantages of neater and more compactness of construction, and including the sleeve member which shields and conceals the spring element 32 in all positions of adjustment of the device. 100

From the foregoing it will be seen that I have devised a neat, simple and practical form construction which fulfills all the desired objects of the invention, the same being automatically or self-adjusting for accommodating the parts thereof to fit or fill out all the parts of the toe and instep of the shoe, which it accomplishes by expanding forwardly and laterally into engagement with the shoe upper on all sides, in 110 response to the action of the spring elements 11 and 15. The turnbuckle form of connection between the heel and toe portion of the form affords provision for an initial positive adjustment for gauging the length 115 of the form to approximately that of the boot or shoe in advance, after which the form automatically adjusts itself to the interior of the boot or shoe without any need of further manual adjustment. The provision of the sectional toe structure with the form of connections shown enables the form to adjust itself neatly and accurately to various styles of toes, such as wide or narrow or pointed toes, as will be obvious 120 by reference to Figure 2.

While I have herein shown and described what I now regard as the preferred form of construction for embodying the proposed improvements, I wish to be understood as 130

reserving the right to make such formal changes or modifications as may fairly fall within the scope of the appended claims.

What I claim is:—

- 5 1. A shoe form comprising a toe portion, and a heel portion, a telescoping rod and tube connecting said toe and heel portions, a coil spring fitted over said rod and abutting against said tube, and a second tube enclosing said coil spring and overlapping one end of said first tube.
- 10 2. A shoe form comprising a sectional toe portion and a heel portion, the toe sections of the form being formed with cylindrical mating recesses each fitted with a sleeve extending somewhat short of the base of the recess, a flexible coil spring having the opposite ends thereof extending through said sleeves and into retaining engagement with
- 15 20 the inner ends thereof, and a connection between said toe sections and the heel portion of the form.
- 25 3. A shoe form comprising a pair of toe sections and a heel section, an approximately horseshoe-shaped spring having its ends pivotally connected with said toe sections,

and a longitudinally adjustable member having one end connected to said heel section and its other end secured to the midpoint of said spring.

4. A shoe form comprising a pair of toe sections and a heel section, an approximately horseshoe-shaped spring having its ends pivotally connected with said toe sections, and a spring-actuated longitudinally expandable member having one end connected with said heel section and its other end secured to the midpoint of said spring.

5. A shoe form comprising a toe portion, and a heel portion, a telescoping rod and tube connecting said toe and heel portions, a coil spring fitted over said rod and abutting against said tube, and a second tube enclosing said coil spring and having one end of said second tube formed with an internal flange engaging one end of said spring, the other end of said second tube fitting telescopically over one end of said first tube.

In witness whereof I hereunto affix my signature.

ARTHUR SCHOSHUSEN.
